UNITED STATES PATENT OFFICE.

LOREN L. WHITNEY, OF HAMMOND, INDIANA, ASSIGNOR TO AMERICAN STEEL FOUNDRIES, OF CHICAGO, ILLINOIS, A CORPORATION OF NEW JERSEY.

REVERSIBLE FULCRUM.

Application filed August 17, 1921. Serial No. 493,011.

To all whom it may concern:

Be it known that I, LOREN L. WHITNEY, a citizen of the United States, residing at Hammond, in the county of Lake and State 5 of Indiana, have invented certain new and useful Improvements in Reversible Fulcrums, of which the following is a specification.

This invention relates to fulcrums and 10 more particularly to fulcrums of the reversible type.

Many reversible fulcrums in use satisfactorily provide the reversible feature but permit a certain amount of lost motion in connections, which is extremely detrimental to 15 its other and important function to a brake beam, that is, the function as a strut of the brake beam truss. Many reversible fulcrums in use also are comparatively difficult to 20 assemble satisfactorily.

One object of my present invention is to provide a simple reversible fulcrum which is easy to assemble and disassemble and which, while permitting the necessary 25 rotational or reversing movement eliminates longitudinal lost motion from the joints which permit reversibility.

Another object is to provide a reversible fulcrum adapted to meet the various requirements under service conditions.

These and other objects are accomplished by means of the arrangement disclosed on the accompanying sheet of drawings, in which—

Figure 1 is a fragmentary top plan view 35 of a brake beam of the truss type embodying my invention;

Figure 2 is a side elevation of the fulcrum with a part thereof in section, the tension 40 and compression members of the brake beam also being shown in section;

Figure 3 is a fragmentary rear elevational view of the brake beam showing the fulcrum;

Figure 4 is a sectional view taken in the plane of line 4—4 of Figure 2, with the fulcrum in its central position; and

Figure 5 is a similar sectional view taken in the same plane showing the fulcrum in 50 one of its operative positions.

The various novel features of the invention will be apparent from the following description and drawings and will be particularly pointed out in the appended claims.

Referring to the figures of the drawings,

it will be noted that I have disclosed my invention in connection with a brake beam of the truss type having a compression member 10, a tension member 11, and fulcrum 12 extending therebetween. The fulcrum includes two spaced arms 13 between which a brake beam lever may be pivoted by the use of a pin, not shown, extending through it and the openings 14 in said arms 13. The rear end of these arms join in a barrel portion 15 which terminates in a head 16 which frictionally engages the web 17 of the compression member 10. The barrel portion 15 has an opening 18 which extends longitudinally of the fulcrum bracket and is in register with an opening 19 in the web of the compression member. A pin 20 extends through the openings 19 and 18 of the compression member and barrel respectively and is provided with a frictional head 21 which frictionally engages the outer side of the web 17 of the compression member. The forward part of the barrel portion 15 of the fulcrum bracket is provided with tapered aligned grooves 22 and 23 which communicate with an opening 24 extending through the forward part of the pin 20. A wedge key 25 is driven through the grooves 22 and 23 and through the opening 24 in the pin 20 whereby the head 16 of the barrel portion 15 is forced into frictional engagement with the inner surface of the web 17 of the compression member 10 and the head 21 is pressed into frictional engagement with the outer surface of the web 17 of the compression member 10. As a result thereof all lost motion between the parts in question is completely taken up and at the same time the fulcrum bracket is frictionally held a sufficient amount to retain the fulcrum bracket in any adjusted position and to prevent accidental movement of said fulcrum bracket with respect to the compression member.

While it is desired to reverse this fulcrum from its right hand position to its left hand position and vice versa, it is also desired to prevent the fulcrum from angling beyond a predetermined point in both directions. To accomplish this result the head 16 of the barrel 15 is provided with angular faces 26 for engaging the upper and lower flanges 27 and 28 of the compression member, as shown particularly in Figure 5.

The front end of the fulcrum bracket 12 is provided with an opening 29 through

which the projection 30 of the tension rod saddle 31 extends. In this particular instance the saddle is provided with upstanding ears 32 for attachment to any suitable supporting hanger.

It is my intention to cover all modifications of the invention falling within the spirit and scope of the following claims.

I claim:

10. 1. In a brake beam, the combination of a compression member, a fulcrum bracket having an end in frictional engagement with said compression member, a pin extending through said compression member and fulcrum bracket and having a head frictionally engaging said compression member, and means for pressing said fulcrum bracket and the head of said pin into engagement with said compression member to yieldably maintain the fulcrum bracket in adjusted position.
15. 2. In a brake beam, the combination of a compression member, a reversible fulcrum bracket having an end in frictional engagement with said compression member, means extending through said compression member and associated with said fulcrum bracket, and means for forcing the aforesaid means and said fulcrum bracket into frictional engagement with said compression member for yieldably retaining the fulcrum bracket in adjusted position.
20. 3. In a brake beam, the combination of a compression member, a reversible fulcrum bracket having an end in frictional engagement with said compression member, means extending through said compression member and associated with said fulcrum bracket, means for forcing the aforesaid means and said fulcrum bracket into frictional engagement with said compression member for yieldably retaining the fulcrum bracket in adjusted position.
25. 4. In a brake beam, the combination of a compression member, a tension member, a fulcrum bracket extending therebetween and having an end in frictional engagement with one of said members, means extending through one of said members and associated with said fulcrum bracket, and means for pressing the aforesaid means and

said fulcrum bracket into frictional engagement with one of said members for yieldably retaining said fulcrum bracket in adjusted position.

5. In a brake beam, the combination of a compression member, a tension member, a fulcrum bracket extending therebetween and having an end in frictional engagement with one of said members, means extending through one of said members and associated with said fulcrum bracket, means for pressing the aforesaid means and said fulcrum bracket into frictional engagement with one of said members for yieldably retaining said fulcrum bracket in adjusted position, and means for limiting said fulcrum bracket in its reversible movements.

6. In a brake beam, the combination of a compression member, a reversible fulcrum bracket, frictional means, and means for forcing a portion of said fulcrum bracket and said frictional means against opposite sides of said compression member for yieldably retaining the fulcrum bracket in adjusted position.

7. In a brake beam, the combination of a compression member, a reversible fulcrum bracket having an end in frictional engagement therewith and provided with means cooperating with said compression member for limiting reversible movements with respect thereto, frictional means, and means for forcing said frictional means and the end of said fulcrum bracket into frictional engagement with said compression member for yieldably retaining the fulcrum bracket in adjusted position.

8. In a brake beam, the combination of a compression member, a reversible fulcrum bracket having an end in frictional engagement with said compression member, a pin extending through said compression member and fulcrum bracket and having a head frictionally engaging said compression member, and a key extending through said fulcrum bracket and pin for pressing said fulcrum bracket and the head of said pin into engagement with said compression member to yieldably retain the fulcrum bracket in adjusted position.

Signed at Hammond, Indiana, this 12th day of August, 1921.

LOREN L. WHITNEY.
